CLAIM

The ornamental design for a tire, as shown and described.

DESCRIPTION

FIG. 1 is a perspective view of a tire, showing our new design;

FIG. 2 is a front elevation left side elevation view of the tire;

FIG. 3 is a top elevation view of the tire;

FIG. 4 is a bottom elevation view of the tire;

FIG. 5 is a left side view of the tire;

FIG. 6 is a right side view of the tire; and,

FIG. 7 is an enlarged view of FIG. 2, showing a portion thereof, the tread pattern repeating around the circumference of the tire.

The portions of the tire depicted in broken dashed lines of uneven length mark the boundaries of the claimed design. The portions of the tire depicted in short broken dashed lines of even length form no part of the claimed design. The long broken dashed lines of even length depict a border of an enlarged portion of the tire and form no part of the claimed design.
